UNITED STATES PATENT OFFICE.

ALBERT J. BATES, OF CHICAGO, ILLINOIS.

MACHINE FOR FORMING TRUSSED METAL STRUCTURES.

1,083,180.

Specification of Letters Patent. Patented Dec. 30, 1913.

Application filed March 29, 1913. Serial No. 757,716.

To all whom it may concern:

Be it known that I, ALBERT J. BATES, a citizen of the United States, residing at Chicago, in the county of Cook and State of Illinois, have invented certain new and useful Improvements in Machines for Forming Trussed Metal Structures, of which the following is a specification.

This invention relates in general to metal working machines and has more particular reference to machines for forming trussed metal structures from slotted metal blanks, the purpose being to stretch one portion of a blank, of this character, away from its original position so that the same will form a tension member and to upset or compress longitudinally another portion of the blank to form a compression member, the trussed structure when completed being shaped and proportioned so as to be suitable for use as the side frame of a railway truck, or the like.

One of the objects of the present invention is the provision of a machine of the character above indicated by means of which the method of forming trussed metal structures disclosed in my application Serial Number 757,717, filed March 29, 1913, may be practised.

Another object is to provide a machine which will hold a metal blank of the desired shape and will automatically and simultaneously stretch one portion of the blank to produce a tension member and upset or compress longitudinally another portion of the blank to produce the compression members of a trussed structure and which shall be strong and durable and efficient in operation and, at the same time, simple in construction and cheap to manufacture.

Other objects and many of the attendant advantages of the invention will be apparent as the same is better understood by reference to the following description when considered in connection with the accompanying drawings by means of which a preferred embodiment of the invention is illustrated.

Referring to the drawings—Figure 1 is a plan view of a machine embodying my invention; Fig. 2 is a similar view showing the position that certain parts assume before the operation of the machine is begun; Fig. 3 is a transverse view of the machine, certain parts being shown in section; Fig. 4 is a lon-

gitudinal sectional view showing the position of the parts at the completion of an operation; Fig. 5 is a fragmentary perspective view of the central section of the bed; Fig. 6 is a plan view of a blank upon which my present machine is designed to operate; and Fig. 7 is a similar view of the completed structure formed by means of my machine from the blank shown in Fig. 6.

By reference to the drawings, it will be observed that the machine comprises a heavy base or frame, designated generally by reference character 11 upon which the operating parts are mounted. Upon the frame in suitable bearings 12 and 13 I have mounted a longitudinally movable shaft 14 which, in the present instance, is shown as provided with threads and between the bearings 12 and 13 there is mounted on the shaft 14 a nut 15 having threaded engagement with the shaft. The nut is rotated by a gear wheel 16 to which it is rigidly secured and this gear, in turn, is actuated from a drive pinion 17 fixed upon a drive shaft 18 which is equipped with loose and fast pulleys 19 and 21, respectively, through which the machine receives its power from any suitable source. It will be manifest that rotation of the nut 15 through the driving mechanism disclosed will cause the shaft 19 to travel longitudinally in its bearings.

Upon the inner end of the shaft 14 I have mounted a cross-head 22 to which are connected the means for stretching the tension member and the means for upsetting the compression member of the blank to be operated upon.

Vertically disposed shafts or pintles 23 are carried at each side of the machine in appropriate bearings 24 and to the top of each shaft is fixedly secured an arm 25 having an enlarged base 26 at its pivotal end upon which an end section 27 of the bed which supports the blank is carried. The bed also comprises a central section 28 provided at its inner edge with tongues 29 which fit in similarly shaped grooves in the opposed faces of the end sections 27, thereby connecting the central section with the end sections in such a way that the end sections are permitted to slide longitudinally of the central section but are restricted from transverse movement relatively to the central section. The central section is slid-

ably supported intermediate its ends upon a stationary guideway or track 31 fixed to the main frame of the machine.

It will be observed from Fig. 2 that the 5 end sections 27 are provided with grooves 32 disposed in alinement with and forming a continuation of a similar groove 33 in the central section 28. These grooves are adapted to receive one of the flanges 34 of the 10 blank 35 when the blank is placed on the bed with the flanges disposed downwardly. The end members are also provided at the opposite sides with corresponding grooves 36 adapted to receive the other flange of 15 the blank, but it will be observed that these grooves and the forward walls of the end sections are omitted throughout the major portion of their length so that no obstruction is offered to the stretching of the tension member in an edgewise direction toward 20 the driving end of the machine.

The bed above described provided with the grooves as shown is particularly adapted to receive a channel-shaped blank such as 25 is shown in Fig. 6, but, if it should be desirable to operate upon blanks of different form, the bed, of course, would be shaped to correspond with the contour of the particular blank employed. The blank as 30 shown in Fig. 6 is provided with a longitudinally extending slit 37 and before being placed in the machine is preferably heated to facilitate the stretching and upsetting operations. The blank after being positioned on 35 the bed with the flanges disposed downwardly is clamped to the central section 33 by a clamping bar or plate 38 which is forced down against that portion of the blank on one side of the slit 37 by hand-operated nuts 39 threaded onto suitable studs 40 or pins 41 projecting upwardly from the central member 28 through elongated slots 42. These slots permit the withdrawal of 45 the clamping plate from operative position so that a blank may be disposed on the bed. The blank is clamped to the end sections 27 of the bed by clamping bars 43 pivoted to the sections at 44 and adapted to be swung into engagement with pins 45, hand-operated nuts 46 being employed to force the 50 bars into clamping position.

For the purpose of stretching the unclamped portion of the blank edgewise away from its original position, substantially into 55 the shape shown in Fig. 7, I have secured upon the cross-head 22 a pair of grooved members 47 which are adapted to receive one of the downturned flanges of the blank. These grooved members are spaced a short 60 distance apart and are connected by a bar 48 which travels upon and is guided by an extension 49 of the bed support 31. Prior to the placing of a blank in the machine the cross-head is moved toward 65 the bed until the grooved members 47

are disposed in alinement with the grooves 36 of the end sections 27 so that when a blank is placed on the bed one of its flanges will be engaged in the grooves of the members 47. Suitable buttons 51 pivoted at 52 on the grooved members are then turned into the position shown in Figs. 1 and 4 to hold the flange of the blank in engagement with these members. The cross-head is then drawn away from the bed by 70 longitudinal movement of the shaft 14 to stretch the portion of the blank engaged by the groove members away from the clamped portion held by the bed. In order to prevent distortion of the flange engaged in the 75 groove during the stretching action, I have mounted upon the sides of each grooved member 47 a hook 53 which is adapted to drop into the position shown in Fig. 4 behind the portion of the blank being stretched 80 as soon as an initial separation of this portion from the bed has been made. In operation it is preferable to perform the initial stretching through engagement of the 85 grooved members with the flanges, as previously described, after which the operating mechanism may be reversed to relieve the tension on the parts and permit the hooks 53 to drop into operative position as shown in Fig. 4. During the completion of the 90 stretching movement the greater part of the strain is taken by these hooks and the flange of the tension member being formed will be relieved of excessive strains so that danger 95 of distorting the same is eliminated. 100

For the purpose of upsetting or longitudinally compressing the clamped portion of the blank to produce the compression member of the completed structure, I have connected the end sections 27 of the bed with 105 the swinging arms 25 so that these sections are moved longitudinally toward each other to exert a longitudinal compression upon the blank during the stretching operation. With this end in view each arm 25 is provided 110 adjacent its pivot with an upwardly projecting pin or stud 54 which seats in a socket or depression in its respective end section 27. The extremities of the arms 25 are connected to the cross-head 22 by links 55 so that the arms are swung from full line position in Fig. 3 to dotted line position shown in said figure as the cross-head moves away from the bed from the position shown in Fig. 2 to that shown in Figs. 1 and 4. The 115 studs 54 during the swinging movement of the arms travel in arcs about the pivotal shafts 23, as will be obvious from Fig. 2, thereby forcing the end sections 27 longitudinally toward each other to exert the 120 required compression upon the compression member of the blank and upset the metal the required amount. It will be manifest that the end sections of the bed travel in an arc, and that the bed as a whole has a slight 125 130

transverse movement which is incidental rather than necessary. The central section 28 of the bed is permitted to travel transversely with the end sections upon the track 5 or guides 31 as has been previously explained.

In the operation of the machine the parts are first moved to the position shown in Fig. 2 and the clamping plate 38 and the clamping bars 43 are moved to inoperative position to permit the placing of a blank on the bed. The blank having previously been slited and also heated to facilitate the stretching and upsetting operations is 15 placed on the bed with the flanges extending downwardly. The clamps 38 and 43 are then moved to operative position to firmly clamp the blank and the buttons 51 are swung into the position shown in Figs. 1 20 and 4 to prevent withdrawal of the blank flange from the grooved members 47. The driving mechanism of the machine is now set in operation to withdraw the cross-head from the bed. After the initial movement 25 has been effected the tension is released to permit the hooks 53 to drop into operative position. The mechanism is then again set in operation and a portion of the blank is stretched until it assumes substantially the 30 position shown in Fig. 1 to provide the tension member of the structure. At the same time the movement of the cross-head through the instrumentality of the arms 25 causes the end sections of the bed to move 35 longitudinally toward each other thereby exerting longitudinal compression upon the blank carried by the bed sufficiently to upset the metal of the compression member and reduce the structure to the desired 40 length. This compression, of course, increases the length of the tension member and enables this member to be stretched to the required position without rupturing or 45 weakening the metal.

The completed structure produced by this machine comprises, as shown in Fig. 7, the stretched tension member 54 and the upset compression member 55 integrally connected at their ends, this structure being 50 suitably shaped and proportioned for use as a side frame in the construction of rail-way car trucks.

It is believed that my invention and its mode of operation will be understood from 55 the foregoing without further description and it will be manifest that many variations in structure may be resorted to within the scope of the following claims.

I claim:

1. In a machine for forming trussed metal structures from slitted metal blanks, the combination of a sectional bed adapted to receive a blank, means to clamp the blank on the bed, means for moving one portion 5 of the blank away from the clamped por-

tion and simultaneously elongating the moved portion, and means for moving one end section of the bed toward the other end section to exert a longitudinal compression upon said clamped portion of the blank. 70

2. In a machine for forming trussed metal structures from slitted metal blanks, the combination of a bed comprising a central section and end sections, clamps mounted on said bed, stretching means adapted to be 75 engaged with a blank positioned on said bed, mechanism for withdrawing said stretching means from the bed to elongate the portion of the blank engaged by said stretching means, and means for moving said end sections of the bed toward each other. 80

3. In a machine for forming trussed metal structures from slitted metal blanks, the combination of a bed comprising a central section and end sections provided with 85 grooves to receive the flanges of a channel-shaped blank, a cross-head, means for connecting the cross-head with one edge of a blank on the bed to displace and elongate one portion of the blank, mechanism for 90 moving said cross-head away from said bed, and operative connections between the cross-head and the end sections of the bed whereby said end sections are moved toward each other by the cross-head during its movement 95 away from the bed.

4. In a machine for forming trussed metal structures from slitted metal blanks, the combination of a bed adapted to receive the blank to be operated upon, a cross-head movable toward and from said bed, grooved members secured to said cross-head and adapted to engage a downwardly projecting flange of a channel-shaped blank on said bed, means for holding the blank flange 100 in said grooved members, and hooks adapted to coöperate with said grooved members to stretch a portion of the blank away from the bed. 105

5. In a machine for forming trussed metal structures from slitted metal blanks, the combination of a sectional bed adapted to receive a channel-shaped blank, a cross-head mounted to move toward and from said bed, means carried by the cross-head 110 for engaging with said blank, a pair of pivotally mounted arms disposed beneath said bed, links connecting the free ends of said arms with the cross-head, and connections between said arms and the bed sections 115 120 whereby the bed sections are moved relatively to each other upon movement of the cross-head.

6. In a machine for forming trussed metal structures, the combination of a bed comprising a central section and end sections, a centrally disposed guide upon which the central section is adapted to travel, a cross-head, a pair of arms pivoted beneath the end sections of the bed, studs projecting 130

- upwardly from said arms into engagement with the end sections of the bed, links connecting the free ends of said arms with said cross-head, and mechanism for moving said cross-head toward and from the bed, the end sections of the bed being moved from and toward each other simultaneously with the movement of the cross-head.
7. In a machine for forming trussed metal structures, the combination of a sectional bed, a longitudinally movable shaft, a rotatable nut engaged with said shaft to move the same longitudinally upon rotation of the nut, means movable with the shaft adapted to engage the flange of a metal blank on said bed, and connections between said shaft and the end sections of said bed whereby upon movement of the shaft in a longitudinal direction the end sections are moved toward and from each other.
8. In a machine for forming trussed metal structures, the combination of a sectional bed adapted to receive a slotted metal blank, a shaft mounted to move longitudinally toward and from said bed, a cross-head connected with said shaft, means carried by said cross-head constructed to engage with one edge of the metal blank on said bed, and connections between the end sections of the bed and said cross-head for moving the end sections together to com-

press the portion of the blank on the bed when the cross-head is withdrawn from the bed to draw a portion of the blank away from the bed.

9. In a machine for forming trussed metal structures from slotted metal blanks, the combination of a sectional bed adapted to support a blank, mechanism for grasping one edge of said blank, means for moving said mechanism toward and from the bed, and levers connected with the end sections of the bed and operable by said means to move said end sections toward and from each other.

10. In a machine for forming trussed metal structures, the combination of a sectional bed comprising a longitudinally movable section, a cross-head, an arm pivoted beneath the movable section of the bed, a stud projecting upwardly from said arm into engagement with said movable section, a link connecting the free end of said arm with said cross-head, and mechanism for moving said cross-head toward and from the bed, the movable section of the bed being moved longitudinally simultaneously with the movement of the cross-head.

ALBERT J. BATES.
